P. BURKHARDT

RECEPTACLE

Filed Jan. 11, 1924

Patented Oct. 28, 1924.

1,512,976

UNITED STATES PATENT OFFICE.

PAUL BURKHARDT, OF ALBION, MICHIGAN, ASSIGNOR TO THE UNION STEEL PRODUCTS COMPANY, LTD., OF ALBION, MICHIGAN.

RECEPTACLE.

Application filed January 11, 1924. Serial No. 685,584.

To all whom it may concern:

Be it known that I, PAUL BURKHARDT, a citizen of the United States, residing at Albion, county of Calhoun, State of Michigan, have invented certain new and useful Improvements in Receptacles, of which the following is a specification.

This invention relates to improvements in receptacles.

10 My improved receptacle is especially designed by me as a garbage burner, that is, a receptacle in which waste paper and the like may be burned, although it is desirable for use for numerous other purposes.

15 The main objects of this invention are to provide a receptacle adapted as a garbage burner which may be effectively secured in closed position or swung to and will remain in open position.

20 Further objects, and objects relating to structural details, will definitely appear from the detailed description to follow.

I accomplish the objects of my invention by the devices and means described in the 25 following specification. The invention is clearly defined and pointed out in the claims.

A structure which is a preferred embodiment of my invention is clearly illustrated in the accompanying drawing, forming a 30 part of this application, in which:

Fig. I is a perspective view of my improved embodiment in a garbage receptacle, the cover being in closed position.

Fig. II is a detail vertical section with 35 the cover in open position.

In the drawing similar reference characters refer to similar parts throughout the several views.

Referring to the drawing, I provide a receptacle formed of wire and comprising bottom hoops 1, top hoop 2 and intermediate hoops 3, the wire slats 4 being secured in spaced relation to these hoops.

40 The bottom 5 is formed of a suitable rim and cross pieces of wire, the bottom being supported in an elevated position relative to the bottom hoop 1.

The cover comprises a rim 6 and cross pieces 7 and 8 of wire, the cross pieces being spot welded to the rim and to each other.

50 To support the cover for tilting and sliding adjustment I provide a pair of support members 9 secured to the undersides of the cover cross pieces at their inner ends, the

supports illustrated being formed of a single piece of wire folded upon itself, the bight 10 being spot welded to the underside of the cover, the outer ends of the supports being free but provided with upwardly turned hooks 11 which embrace the rim 6. 60 These supports are engaged under the rim, the hooks permitting the ready engagement and disengagement of the cover with the rim.

The supports are provided with offsets at 65 12 which serve as stop shoulders to support the cover in open position at the side of the receptacle, as shown in Fig. III.

A handle 13 also formed of wire is secured to the central cross piece of the top.

70 The spring latch 14 is formed of wire and secured to cross pieces opposite the cover supports, this latch having a downwardly curved outer end 15 projecting below and beyond the rim so that the latch 75 may be disengaged with the top hoop of the receptacle by a sliding motion.

With the parts thus arranged, the cover is secured to the receptacle so that the receptacle may be carried by means of the 80 cover handle when the cover is closed. The cover is held in closed position when the contents of the receptacle are to be burned and is entirely out of the way when open.

The structure is economical to produce 85 and at the same time very strong and durable and easily manipulated.

Having thus described my invention, what I claim as new and desire to secure by Letters Patent, is:

90 1. The combination with a receptacle provided with a top hoop, of a cover comprising a rim and cross pieces, a pair of spaced cover supports disposed below said hoop and secured at their inner ends to the underside of said cover centrally thereof and having hooks at their outer ends embracing said rim whereby they may be engaged and disengaged with said hoop and the cover is supported for sliding and tilting movement, 95 the inner ends of said supports being upwardly offset spacing the supports from the top and providing stop shoulders for the cover when swung to open position at the side of the receptacle, and a spring latch 100 secured to the cross pieces of the cover opposite the said support and having a downwardly offset free end disposed below and 105

projecting beyond the rim to be engaged with or disengaged from the top hoop by a sliding movement of the cover.

2. The combination with a receptacle 5 provided with a top hoop, of a cover comprising a rim and cross pieces, and a pair of spaced cover supports disposed below said hoop and secured at their inner ends to the underside of said cover centrally 10 thereof and having hooks at their outer ends embracing said rim whereby they may be engaged and disengaged with said hoop and the cover is supported for sliding and tilting movement, the inner ends of said 15 supports being upwardly offset spacing the supports from the top and providing stop shoulders for the cover when swung to open position at the side of the receptacle.

3. The combination with a receptacle 20 provided with a top hoop, of a cover provided with a rim, a pair of spaced cover supports disposed below said hoop and secured at their inner ends to the underside of said cover and having hooks at their 25 outer ends embracing said rim whereby they may be engaged and disengaged with said hoop and the cover is supported for sliding and tilting movement, and a spring latch secured to said cover opposite said 30 support and having a downwardly offset free end disposed below and projecting beyond the rim to be engaged with or disengaged from the top hoop by a sliding movement of the cover.

4. The combination with a receptacle 35 provided with a top hoop, of a cover provided with a rim, and a pair of spaced cover supports disposed below said hoop and secured at their inner ends to the underside of said cover and having hooks at their outer ends embracing said rim whereby they may be engaged and disengaged with said hoop and the cover is supported 40 for sliding and tilting movement.

5. The combination with a receptacle 45 provided with a top hoop, of a cover provided with a rim, and a pair of spaced cover supports secured at their inner ends to the underside of said cover in a spaced 50 relation to the rim, said support members being disposed under said hoop and having hooks at their outer ends whereby they may be engaged and disengaged with the hoop and the cover is supported for sliding and tilting movement, said supports having shoulders constituting stops for supporting said cover in open position when 55 swung to the side of the receptacle.

6. The combination with a receptacle 60 provided with a top hoop, of a cover provided with a rim, and a pair of spaced support members secured at their inner ends to the underside of said cover in a spaced

relation to the rim to engage said hoop whereby the cover is supported for sliding and tilting movement, and the cover supported in open position at the side of the receptacle.

7. The combination with a receptacle 65 provided with a top hoop, of a cover provided with a rim, a cover support disposed below said hoop and secured at its inner end to the underside of said cover, said support member having a hook at its outer end embracing said rim permitting the engagement and disengagement with said hoop and supporting the cover for sliding and tilting movement, the inner end of said support being upwardly offset, spacing the support from the top and providing a stop shoulder for the cover when swung to open 70 position at the side of the receptacle, and a spring latch secured to the cover opposite the said support and having a downwardly offset free end disposed below and projecting beyond the rim to be engaged with or disengaged from the top hoop by a sliding 75 movement of the cover.

8. The combination with a receptacle 80 provided with a top hoop, of a cover provided with a rim, and a cover support disposed below said hoop and secured at its inner end to the underside of said cover, said support member having a hook at its outer end embracing said rim permitting the engagement and disengagement with 85 said hoop and supporting the cover for sliding and tilting movement, the inner end of said support being upwardly offset, spacing the support from the top and providing a stop shoulder for the cover when swung to open 90 position at the side of the receptacle.

9. The combination with a receptacle 95 provided with a top hoop, of a cover provided with a rim, a cover support secured to the underside of said cover and slidably embracing said cover whereby the cover is supported for tilting and sliding adjustment and may be swung to open position at the side of the receptacle, and a spring latch secured to said cover whereby said support is adapted to be engaged and disengaged with the top hoop by a sliding movement of the cover.

10. The combination with a receptacle 100 provided with a top hoop, of a cover provided with a rim, and a cover support secured to the underside of said cover and slidably embracing said cover whereby the cover is supported for tilting and sliding adjustment and may be swung to open position at the side of the receptacle.

In witness whereof, I have hereunto set my hand.

PAUL BURKHARDT. [L.S.]
